BOMB PROTECTION APPARATUS

Francisco Feitosa, New York, N. Y.

Application December 16, 1936, Serial No. 116,126

2 Claims. (Cl. 89—36)

This invention relates to bomb protection apparatus, an object of the invention being to provide an apparatus which may be located on a building, bridge, or any other location and which will function to protect the structure from aerial bombs dropped by aircraft and the like.

More specifically the invention includes a series of spaced, superimposed nets located above the structure to be protected, said nets varying in strength and texture and having differing spring tension means which operate singly or together to check the fall of a bomb and prevent its explosion, thus protecting the structure below.

The invention embodies many novel features of construction and combinations and arrangements of parts, all of which will be more fully herein-after described and pointed out in the claims.

In the accompanying drawings—

Fig. 1 is a broken view in elevation illustrating my improved apparatus in operative position on top of a structure, which for convenience of description will hereinafter be assumed is a building;

Fig. 2 is a sectional end elevation on the line 2—2 of Fig. 1;

Fig. 3 is a fragmentary sectional plan view on the line 3—3 of Fig. 1;

Fig. 4 is a fragmentary view in side elevation of one end of the apparatus, illustrating by dot-and-dash lines the varying positions of the parts.

10 represents a building or other structure on top of which my improved apparatus is located. This apparatus preferably comprises a suitable base frame 11, having at its ends brackets 12 in which uprights are pivotally mounted. These uprights are located at the ends of the frame and are arranged in sets. While, of course, the invention is not limited to any specific number of these uprights I have shown for purposes of illustration three sets of uprights at each end of the frame and have given these sets of uprights the reference characters 13, 14, and 15, respectively. While each set of uprights may consist of any desired number, I have shown for purposes of illustration three uprights in each set. The uprights 13 are the shortest of the sets, the uprights 14 of greater length than the uprights 13, and the uprights 15 are of greater length than the uprights 14. These sets of uprights are connected, respectively, by cross bars 16, 17 and 18 so that the several sets of uprights and their cross bars form vertically disposed pivoted frames which support nets, the uppermost net 19 connected to the cross bars 18, the next lower net 20 connected

to the bars 17, and the lowermost net 21 connected to the bars 16. Thus the apparatus provides a series of normally horizontal superimposed nets spaced apart, and while I have shown three of these nets it is obvious that the specific number may be varied. The uppermost net 19 is the weakest, the next lower net 20 is stronger, and the lowermost net 21 is the strongest of the three. This varying strength may be accomplished by the texture and mesh of the nets and also by varying tensioning means which I employ and which will now be described.

Rigid horizontal arms 22 are fixed in any desired manner to the building structure or to the base frame 10, and are located preferably at the ends of the building and project outwardly therefrom as clearly illustrated. These arms are connected to the pivoted frames above described either to the cross bars 16, 17, and 18, or to the uprights 13, or to both as clearly shown, by means of flexible stays 23 which have embodied in their length coil springs 24. These springs 24 are of varying tension, the strongest springs being within the stays connected to the shorter frames and the other springs being successively lighter. To strengthen these arms 22, bracing cables 25 may connect the arms with the building structure below the same, and these cables may have suitable turnbuckles 26 therein to adjust the cables. The cross bars 18 of the longer frames are provided with upwardly projecting deflecting frames 26'. These frames 26' may be formed in any desired manner but I have shown them as consisting of uprights connected by a cross bar or rod 27. To provide means for positively limiting the inward movement of the frames and also the sag of the nets, I have shown ropes or cables 28 connecting the outer ends of the arms 22 with the upper portions of the frames, there being sufficient slack in said cables to allow the frames to move and the nets to sag, but when this slack is taken up the frames and nets are stopped from further movement.

The operation of the apparatus is as follows: When a bomb falls on the uppermost net 19, it will cause the net to sag and if the bomb is sufficiently light and its momentum can be checked by the net, the uppermost net will alone function to catch the bomb and prevent its explosion. If, however, the weight of the bomb or its momentum is sufficient it will not only force downwardly and cause the upper net to sag but it will also cause the second net to sag, and so on, until the third net may be caused to sag by a bomb of sufficient weight and force. In any event the

series of nets are sufficiently strong and have sufficient tension to stop the fall of any aerial bomb without exploding the same. The deflecting frames 26' which project above the longer end frames are arranged so that should a bomb fall in a plane which would strike the pivoted frames, the deflecting frames will serve to contact with the bomb and cause it to be deflected so that it will not injure or destroy the vertically positioned pivoted frames.

5 While I have illustrated and described what I believe to be a preferred embodiment of my invention, it is obvious that various slight changes may be made with regard to the form and arrangement of parts without departing from my invention, and hence I do not limit myself to the precise details set forth but consider myself at liberty to make such changes and alterations as fairly fall within the spirit and scope of the claims.

10 20 I claim:

1. A bomb protection apparatus including a base frame, a series of upright frames of vary-

ing heights pivotally connected to the base frame, nets connecting the upper ends of pairs of said upright frames, fixed arms extending horizontally from the base frame, stays connecting said arms with the upright frames, coil springs constituting portions of said stays, and cables connecting said arms and said upright frames, said cables limiting the inward pivotal movement of the frames and the sag of the nets.

2. A bomb protection apparatus including a base frame, a series of upright frames of varying heights pivotally connected to the base frame, nets connecting the upper ends of pairs of said upright frames, fixed arms extending horizontally from the base frame, stays connecting said arms with the upright frames, coil springs constituting portions of said stays, cables connecting said arms and said upright frames, said cables limiting the inward pivotal movement of the frames and the sag of the nets, and bomb deflecting frames secured to the upper ends of the highest net-supporting frames.

15 20 FRANCISCO FEITOSA.
